(57) **CLAIM**

The ornamental design for a hair straightening iron as shown and described.

DESCRIPTION

1. Hair straightening iron

Fig. 1.1 is a perspective view of a hair straightening iron showing the new design;

Fig. 1.2 is a side view thereof;

Fig. 1.3 is a top view thereof;

Fig. 1.4 is a bottom view thereof;

Fig. 1.5 is a front view thereof;

Fig. 1.6 is a rear view thereof;

Fig. 1.7 is a perspective view of the hair straightening iron shown in an open configuration;

Fig. 1.8 is a side view of the hair straightening iron shown in an open configuration.

(Continued)

The broken lines shown in the drawings depict portions of the hair straightening iron that form no part of the claimed design.

1 Claim, 8 Drawing Sheets
